UNITED STATES PATENT OFFICE.

FREDERICK HACHMANN, OF ST. LOUIS, MISSOURI, ASSIGNOR OF ONE-EIGHTH TO DAVID M. HUTCHINSON, OF FERGUSON, MISSOURI.

BOTTLE-CLOSURE.

1,319,067.

Specification of Letters Patent.

Patented Oct. 21, 1919.

Application filed January 20, 1919. Serial No. 271,980.

To all whom it may concern:

Be it known that I, FREDERICK HACHMANN, a citizen of the United States, and resident of the city of St. Louis and State of Missouri, have invented certain new and useful Improvements in Bottle-Closures, of which the following is a specification containing a full, clear, and exact description, reference being had to accompanying drawings, forming a part thereof.

My invention relates to certain new and useful improvements in bottle closures and has for its primary object a removable closure for milk bottles, the same being provided with securing means adapted to be inserted on the inside of the mouth of a bottle, so that the exterior of the bottle mouth is free at all times to be kept in a clean and sanitary condition.

20 In the drawings:

Figure 1 is a side-elevation of a portion of a bottle with parts broken away, showing my invention applied thereto.

Fig. 2 is a cross-sectional view of the 25 same.

Fig. 3 is an inverted perspective view of the cap and securing member.

Fig. 4 is a plan view of the securing member before being bent into shape for use.

30 Referring to the drawings, 4 indicates a fragment of a bottle neck having the usual mouth edge or rim 5. 6 indicates the lid of my improved closure, which is stamped from a piece of sheet metal and is provided 35 on its underneath surface with a groove 7, which is adapted to snugly fit over the top edge 5 of the bottle neck.

The lid 6 is provided with a spring actuated handle 8, which is formed integral 40 with the lid 6, said handle being provided with perforated ears 9.

10 indicates the securing member for my closure, which is formed of a resilient or elastic piece of metal, which is adapted to 45 be bent inwardly for insertion on the inside of the bottle neck and by expansive force will firmly secure the closure in place on the bottle neck. Secured to the resilient or elastic band or securing member 10 is 50 an arm 11, which has a horizontal portion 12 which seats or fits in a depression 13 formed in the lid 6, so as to permit the lid to snugly seat on the top edge of the bottle neck.

Formed on one end of the vertical de- 55 pending portion 14 of the arm 11 are studs

or projections 15 which are adapted to be inserted in the perforated ears 9 carried by the handle 8. Mounted on these projections or studs 15 are coil springs 16 one on each side of the arm, the same being connected 60 together by a loop 17, which is seated beneath the arm 11.

The free ends 18 of the springs 16 rest beneath the handle 8. By means of these springs, the lid is spring held on the top 65 of the bottle neck.

In order to apply my closure to a bottle, the resilient member 10 is put under compression and forced on the inside of the bottle neck and, as previously stated, is 70 held in position by the expansive force of the member 10.

In order to open or lift the lid, all that is necessary is a slight pressure against the outside of the handle 8. By locating the 75 securing member 10 on the inside of the neck, the exterior surface of the bottle neck is left unobstructed. The ends of the securing member 10 are spaced apart as at 19, for not only permitting the member to 80 be compressed for insertion in the bottle neck, but also as a free opening or space for the discharge of the contents of the bottle. The member 10 is of sufficient size to snugly fit in the usual recess 20 formed on the inside of the bottle neck and, when seated, is flush with the inside of the bottle neck and its top edge.

The securing member 10 is preferably stamped as illustrated in Fig. 4.

Having fully described my invention, what I claim is:

1. A bottle closure for milk bottles and the like comprising a compressible securing ring member adapted to be inserted on the inside of the bottle neck and being flush with the inside and top edge of the neck, an arm formed integral with said compressible ring like member and provided with studs and projecting above and beyond the bottle neck, and a spring held lid pivotally mounted on said studs.

2. A bottle closure for milk bottles and the like comprising a circular band of resilient material adapted to be seated by compression on the inside of the bottle neck and held therein by its expansive force, an arm secured to said circular band and lying above the top edge of the bottle neck and projecting outwardly beyond the same, a 110

spring held lid provided with an operating handle and with a depression to receive said arm.

3. A bottle closure for milk bottles and the like comprising a resilient circular band adapted to be inserted on the inside of the bottle neck and held on the inside thereof by means of the expansion of said band, an arm secured to said band and lying above the top edge of the bottle neck and provided with a horizontal portion and depending vertical portion, a spring held lid provided

with an operating handle, and a depression to receive the horizontal portion of the arm, said lid being pivotally secured to the depending vertical portion of said arm. 15

In testimony whereof, I have signed my name to this specification in the presence of two subscribing witnesses.

FREDERICK HACHMANN.
